(57) **CLAIM**

The ornamental design for a protective sleeve as shown and described.

DESCRIPTION

FIG. 1 is a perspective view of a protective sleeve showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the protective sleeve where the protective sleeve is assembled with the clip.

The broken lines in the drawings depict portions of the protective sleeve, and the rest broken lines illustrating the clip shown in FIG. 9 are directed to the environment. All the broken lines form no part of the claimed design.
